DRY VAPOR GENERATOR

Alfred H. B-Roberts, Los Angeles, Calif.

Application November 9, 1935, Serial No. 49,048

4 Claims. (Cl. 21—125)

My invention relates generally to a device for producing and blending curative dry vapors of certain vegetable or mineral matter with the vapor of medicinal liquids which may be administered to a patient, either internally by inhalation or externally, depending upon circumstances and the constituents employed, and appertains specifically to structural details constituting additions or improvements in the means of my

10 Patent No. 1,282,372, granted October 22, 1918.

The object of my patent above noted of providing a means for the creation of a curative vapor by the destructive distillation of vegetable or mineral matter purified for inhalation alone 15 or supplemented in a blend by gas formed by the agitation of medicinal liquids is also an important object of the present invention.

It is also an object of the present invention to provide a series of receptacles in which medications may be deposited, embodying means to 20 direct variable quantities of vapor through each or any of the receptacles, and permitting a multiplicity of blends of the vapors thus individually generated.

25 Still another object is the provision of a feed receptacle for each medicator, having a manually-operable valve to regulate refilling of the medicators while the device is in operation.

The present invention is further distinguished 30 from my said prior patent by providing, in combination, means for removably associating the receptacles in operative relationship to facilitate cleaning and assembly, comprising a supporting structure to which said receptacles may be secured, having valve-controlled conduits incorporated therein, thus permitting maximum efficiency and economy.

Other objects and corresponding advantages, such, for instance, as durability of construction, 40 facility of operation, and compactness, will be apparent to those of skill in this art upon an examination of the following drawing, in which—

Fig. 1 is a perspective view of my invention;

Fig. 2 is a sectional view on lines 2—2 of Fig. 4;

45 Fig. 3 is a view similar to Fig. 2 on lines 3—3 of Fig. 4;

Fig. 4 is a plan view of my invention as shown in Fig. 1 with the top cover off;

Fig. 5 is a sectional view illustrating diagrammatically the relative position of the various components and the direction of the flow of vapor therethrough;

Fig. 6 is a plan view on lines 6—6 of Fig. 5.

Referring more particularly to the drawing in 55 which like numerals indicate similar parts

throughout the several views, 10 designates a circular base and 11 a compartment conforming to the contour of the base 10 and supported above said base by a pair of columns 12 and 13. The distance that compartment 11 is spaced above base 10 is determined by the length of a series of receptacles, preferably glass, suspended from compartment 11 above the base, as will be hereinafter more in detail described.

A top plate 15 is secured to compartment 11 10 by screws 16 or the like, which provides a roof for passages formed within said compartment. A hole 17 in top plate 15 opens into a chamber 18 in compartment 11, said chamber being formed by walls integral with the floor of said compartment and roofed by plate 15. A furnace comprising a container 19 having an opening 20 in its bottom is adapted to seat in hole 17. Vegetable or mineral matter, designated by the numeral 21, is adapted to be burned in the furnace 20 to create medicinal vapors which are then drawn through opening 20 into chamber 18.

A circular boss 22 internally threaded at 23 is formed integrally with the underside of the floor of compartment 11 into which a receptacle 24, for a liquid purifier 25, having an externally threaded mouth, is removably screwed. A tubular valve 26, having a knob 27 at its upper end for manual rotation, extends through holes in top plate 15 and a wall of compartment 11, into the receptacle 24, opening preferably below the surface of the wash 25. An aperture 28 in valvular tube 26 in the horizontal plane of chamber 18, may be brought into alignment with a hole 29 in the wall of said chamber to permit vapor drawn through opening 20 by a centrifugal blower hereinafter described, to enter receptacle 24. Another hole 30 through the floor of the compartment connects the interior of the receptacle with a second chamber 31 therein. Vapor passing 40 from chamber 18 into chamber 31 through the purifier of receptacle 24 is thus relieved of impurities. A pair of baffles 32 and 33 in chamber 31, formed integrally with the wall of said chamber, causes the vapor from receptacle 24 to be 45 thoroughly mixed and tends to further purify the same.

Column 12 is hollow and is divided in its center by a partition 34 extending all but a short distance from its bottom. The two divisions 35 50 and 36 of the interior of the column thus formed are filled with a purifier through which the vapor entering division 35 through its communication with chamber 31, may be further purified.

As above generally noted, a blower, comprising 55

a centrifugal fan 37, located in the center of compartment 11 and communicated with division 36 by means of a conduit 38 formed in a raised portion of the top plate 15, provides the suction necessary to draw air through furnace 19 and the portion of the device just above described. Motive power for the fan 37 is provided by means of an electric motor 39, secured to the underside of compartment 11 and adapted to rotate shaft 10 40 on which fan 37 is mounted.

A rheostat 41, secured to the floor of the compartment and controlled by a knob 42 on top plate 15 in any manner well known in the art, facilitates the regulation of speed of fan 37.

15 The second hollow column 13 is divided by partition 43 so as to form divisions 44 and 45 connected at their bottom by a hole 46 through the partition in the same manner as is column 12, and is likewise filled with a purifying element 20 well known in the art for cleansing the vapor. The exhaust of the blower is directed through a chamber 47 into division 44 of the column, from which it passes into division 45 through the hole 46.

25 The cleansed vapor is blown from the purifier in column 13 into a curved manifold passage 48. Adjacent manifold 48 are a plurality of vertical tubular valve housings 49 (four being illustrated, though any number may be incorporated in specific embodiments). Valve tubes 50 each extend from above plate 15 through said housings 49 and the floor of the compartment 11 into a respective medicator 51, releasably suspended from a series of circular bosses 52 integral with compartment 11, in the manner described above with respect to receptacle 24. Holes 53 through tubes 50 correspond in size and horizontal alignment with holes 54 in each valve housing. Knobs 55 on the upper end of the valve tubes 50 facilitate 30 individual manual rotation of the valves to align holes 53 and 54 which connect each medicator with manifold 48.

To facilitate refilling of the medicators while the device is in operation, a drip feed device is provided for each medicator comprising the following: Each valve tube 50 incloses a smaller tube 56 which extends from slightly below the lower end of tube 50 upwardly through and above knob 55. At the upper end of tube 56 a receptacle 57 is supported in which a supply of the medicament contained in the medicator therebelow may be stored and fed into the medicator through the latter tube. A needle valve 58, of any form well known in the art, is shown operatively supported in the receptacle 57, to close the bore of tube 56, by means of a web 59 secured integrally with the edge of the receptacle. If it is desired to employ my invention without the drip feed device, it may be easily removed without affecting the operation, and a plug (not shown) inserted into the bore through knob 55. Vents 60 through the floor of the compartment connect each medicator 51 with an individual passage 61 within the compartment 11. A mixing jar 62 located between the medicators 51 is threaded to a boss 63 integral with the bottom of the compartment. Each of passages 61 separately extends over said mixing jar 62, and each is connected therewith by a separate hole 64 through the floor of the compartment.

A heating element comprising a resistance coil 65 is provided in jar 62 supported at each end to insulators (not shown) mounted in the floor of compartment 11 and connected by wires 66 to 75 a rheostat 67 secured to the underside of com-

partment 11 by screws or the like. The actuation of rheostat 67 is controlled by knob 68 on top plate 15 by means obvious to all of skill in this art.

69 indicates an exit pipe (Figs. 1 and 3) from mixing jar 62 extending through the inclosure and top plate 15, which is adapted for connection with a tube (not shown) to lead the treated vapor to the place of its use.

Provision for varying the strength of the vapor 10 created in and drawn through furnace 19 is made by means of holes provided in the top plate 15 on each side of the furnace, in which cylinders 71, opening into chamber 18, are secured, through which air is adapted to pass to relieve suction 15 created in said chamber by fan 37. The upper end of each cylinder is partially closed, forming an off-center opening 70. A valve 72 comprising a cap seated on the upper end of each cylinder, has a hole 73 therein which may be brought into 20 partial or complete registry with holes 70 in the end of cylinder 71 by rotation. A manually-operable pulley 74 is rotatably mounted on top plate 15 by means of a screw 75 or the like adjacent cylinders 71. A belt indicated at 76 is looped around each of valves 72 and pulley 74 to convey 25 rotary motion from said pulley to each of said valves, thereby enabling simultaneous operation of the valves.

It will thus be seen that I have provided a 30 practical device in which any of a series of medicinal liquids or other medicaments may be agitated by a thoroughly-cleaned vapor generated by the combustion of mineral and vegetable matter to create curative vapors which may be used 35 individually or combined in any suitable proportion to provide the most healing blend.

Having described my invention, I claim:

1. In a dry vapor producing apparatus, the combination of a base, a compartment supported above said base, a series of circular bosses on the bottom of said compartment, medicators removably secured to said bosses, and a plurality of valve-controlled conduit-passages within said compartment connecting said medicators with a mixing receptacle.

2. In a dry vapor producing apparatus, the combination of a compartment divided into a plurality of passages, said compartment having a floor which also forms the floor of said passages, a purifier contained in one of said passages, a plurality of circular bosses downwardly extending from the floor of said compartment, a medicator removably secured to each of said bosses, a mixing container connected by said passages with each of said medicators, a heating element within said mixing container, and means to direct vapor through said purifier into any of said medicators, and thence into said mixing container.

3. In a device of the character described, the combination of a compartment, a furnace supported in said compartment, a vapor purifier suspended from said compartment, passages connecting said furnace with said purifier, a plurality of downwardly extending annular bosses on the underside of said compartments, a medicator suspended from each of said bosses, a manifold within said compartment connecting said purifier with said medicators, a valve for the inlet opening in each medicator, a conduit from each of said medicators to a mixing receptacle, a heating element within said mixing receptacle, and means to cause vapor from said furnace to flow through said apparatus.

4. In a vapor producing apparatus, the combination of a base, a compartment supported on said base, a furnace in said compartment, a series of circular bosses on the bottom of said compartment, a plurality of medicators suspended from said bosses, a plurality of valve-controlled

conduit passages within said compartment connecting said furnace with said medicators and said medicators with a mixing receptacle, and a heating element within said mixing receptacle.
